UNITED STATES PATENT OFFICE

105,573

DESIGN FOR A DRESS ENSEMBLE

Grace Diaz, New York, N. Y.

Application June 14, 1937, Serial No. 69,819

Term of patent 3½ years

To all whom it may concern:

Be it known that I, Grace Diaz, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

The floral elements on the front and rear portions of the jacket unit of the dress ensemble represent contrastingly colored appliques, as shown.

I claim:

The ornamental design for a dress ensemble, substantially as shown, and described.

GRACE DIAZ.
